DESIGN FOR A YARN BOBBIN OR SIMILAR ARTICLE

Gizella Fowler, New York, N. Y., assignor to C. J. Bates & Son, Chester, Conn., a firm composed of Hamilton C. Bates, Wells C. Bates and Hamilton C. Bates, Jr.

Application July 7, 1944, Serial No. 114,332

Term of patent 14 years

(Cl. D3—19)

To all whom it may concern:

Be it known that I, Gizella Fowler, a citizen of the United States, residing in New York city, in the county of New York and State of New York, have invented a new, original, and ornamental Design for a Yarn Bobbin or Similar Article, of which the following is a specification, reference being had to the accompanying drawing, forming part thereof:

Fig. 1 is a plan view of a yarn bobbin showing my new design; and

Fig. 2 is an edge view of the yarn bobbin shown in Fig. 1.

I claim:

The ornamental design for a yarn bobbin or similar article, as shown.

GIZELLA FOWLER.
